CLAIM

The ornamental design for data processing equipment, as shown and described.

DESCRIPTION

FIG. 1 is a perspective view of data processing equipment showing the new design;

FIG. 2 is a front view thereof;

FIG. 3 is a rear side view thereof;

FIG. 4 is a top plan view thereof;

FIG. 5 is a bottom plan view thereof;

FIG. 6 is a left side view thereof; and,

FIG. 7 is a right side view thereof.

The data processing equipment is shown with a symbolic break in its length. The appearance of any portion of the article in between the broken lines, including the broken lines themselves, forms no part of the claimed design.
